Primary Examiner—Joel Sincavage

(74) Attorney, Agent, or Firm—Rader, Fishman & Grauer,
PLLC(57) **CLAIM**The ornamental design for an electric cable bundling device,
as shown and described.**DESCRIPTION**FIG. 1 is a top, right perspective view of an electric cable
bundling device showing my new design;FIG. 2 is a top, left perspective view thereof;
FIG. 3 is a front elevational view thereof, a rear elevational
view thereof being a mirror image;FIG. 4 is a left side elevational view thereof;
FIG. 5 is a right side elevational view thereof; and
FIG. 6 is a top plan view thereof, a bottom plan view thereof
being a mirror image.FIG. 7 is a top, right perspective view of a second embodiment
of an electric cable bundling device showing my new
design;FIG. 8 is a top, left perspective view thereof; and
FIG. 9 is a top plan view thereof, a bottom plan view thereof
being a mirror image. The rest of views thereof is the same
as those of the embodiment of FIG. 1.FIG. 10 is a top, right perspective view of a third embodiment
of an electric cable bundling device showing my new
design;FIG. 11 is a top, left perspective view thereof;
FIG. 12 is a front elevational view thereof, a rear elevational
view thereof being a mirror image;

FIG. 13 is a left side elevational view thereof; and

FIG. 14 is a right side elevational view thereof.

The rest of views thereof is the same as those of the
embodiment of FIG. 1.FIG. 15 is a top, right perspective view of a fourth embodiment
of an electric cable bundling device showing my new
design; andFIG. 16 is a top, left perspective view thereof.
Top and bottom plan views thereof are the same as those of
the embodiment of FIG. 7. The rest of views thereof is the
same as those of the embodiment of FIG. 10.FIG. 17 is a reference cross-sectional view along the line
17-17 of FIGS. 6 and 9 without showing internal structure;
FIG. 18 is a reference cross-sectional view along the line
18-18 of FIGS. 3 and 12;FIG. 19 is a reference enlarged left side elevational view of
the first embodiment; and,FIG. 20 is a reference top plan view of the embodiment of
FIG. 1, wherein the cables are connected to the both left and
right end portions of the embodiment.The portions in broken lines and FIGS. 17-20 are for
illustrative purpose only and form no part of the claimed
design.**1 Claim, 7 Drawing Sheets**FIG. 1
